(57) **CLAIM**

The ornamental design for a medical spacer for managing IV lines, as shown and described.

DESCRIPTION

FIG. 1 is a perspective view of a spacer showing our new design;

FIG. 2 is a top perspective view thereof;

FIG. 3 is a top plan view thereof; and,

FIG. 4 is a front plan view thereof.

The broken lines showing the IV tubes are included for the purpose of illustrating environmental structure only and forms no part of the claimed design.

1 Claim, 2 Drawing Sheets
